RAIL ANCHOR

Filed Jan. 24, 1927

FIG. 1

FIG. 2

FIG. 4

FIG. 3

INVENTOR
BENJAMIN B. BETTS
By Edward S. Longman
ATTY.

UNITED STATES PATENT OFFICE.

BENJAMIN B. BETTS, OF ST. LOUIS, MISSOURI.

RAIL ANCHOR.

Application filed January 24, 1927. Serial No. 163,048.

My invention relates to improvements in rail anchors, and has for its primary object a rail anchor which is composed of a single piece of bent spring material circular in cross section.

A further object is to construct a rail anchor which has no sharp edges contacting with the base flange of a rail.

By my construction of anchor, while holding the rail against creeping, all possibility of nicking the edges or surfaces of the base flange is prevented on account of it being constructed of round material. I have found that this nicking forms a starting point for the breaking of the rails when loads pass thereover and it is to prevent such nicking caused by sharp edges that I have devised my present structure.

In the drawings:

Fig. 1 is a sectional view of a rail with my device in position;

Fig. 2 is a top plan view of the same;

Fig. 3 is an enlarged perspective of my rail anchor; and

Fig. 4 is an enlarged top plan view of the same.

In the construction of my device I employ a rail anchor which is formed from a single bar of spring material circular in cross section. One end of the bar is provided with an upturned portion 5. Extending from this upturned portion is a horizontal portion 6 which is slightly bowed down, the purpose of which will be explained in detail later. Integral with the portion 6 is an upwardly curved portion 7 which has extending therefrom and toward the upturned portion 5 an inclined arm 8. The arm 8 is provided with a substantially semi-circular bend 9. This bend has an integrally formed arm 10. This arm is inclined the same as the arm 8 but is of slightly less length than the arm 8. Integral with the arm 10 is a bend 11 which terminates in an arm 12. This arm is preferably parallel to the arm 6. The arm 12 terminates in a bend 13 with which a downwardly projecting arm 14 is formed integral.

In Figs. 1 and 2 15 represents a tie, 16 the ball of a rail, 17 the web, and 18 and 19 the base flanges.

The method of attaching my device is as follows: The upturned end 5 is passed underneath the base flanges of the rail in such a manner that the arms 8 and 10 and loop 9 will extend over the top of the base flange 19. The device is then driven on

securely and by reason of it being formed of spring material, the upturned portion 5 snaps upward as soon as it has passed the edge of the base flange 18 and by reason of my construction only the upturned portion 5 and the inside edge of the curved portion 11 will contact with the edges of the base flanges 18 and 19 respectively, while the inside edge of the curved portion 7 will be spaced apart therefrom. This is clearly shown in Fig. 4 wherein the dotted lines represent the edges of the base flanges 18 and 19.

When the device is in position the down-turned portion 14 rests against the tie and in fact acts as a pivot point when the rail creeps in one direction so that the arm 6 together with the projection 5 and the curved portion 11 will have a tendency to skew the device in a direction opposite to the direction of the creep and in so doing the projection 5 and the inside edge of the bend 11 come closer together causing this edge of the bend 11 and the projection 5 to bind tightly against the edges of the base flanges and the more the rail creeps in this direction the tighter this binding action will be, but, due to the fact that there are no sharp edges contacting with the edges of the base flanges, no nicking will occur.

The purpose of making the arm 6 bowed downward is to assure the engagement of the projection 5 since the arm 6 will only contact with the base flanges adjacent their outer edges. In this way any irregularities or curvature of the bottom of the base flanges will not prevent the engagement of the projection 5.

It will be observed that the arm 6, the curved portion 7, the arm 8, the bend 9, the arm 10, the bend 11, and the arm 12 form tapered clamping jaws for securing the device to the base flange of a rail, and contacting with the upper and lower surfaces thereof at longitudinally spaced apart points, which is believed will increase the gripping action of said jaws on the base flange.

One of the important features of my device is that the inner surface of the bend 7 is farther removed from the edge of the base flange than the inner edge of the bend 11. This is for the purpose of permitting my device to take care of the variations in width of the base flanges of a railway rail since the distance between the upward portion 5 and the inner surface of the bend 11

is less than the distance between the upward projection 5 and the inner surface of the bend 7 so that should any variations in width occur, the anchor can be attached to the rail slightly skewed as illustrated in Fig. 4 thereby taking care of any variations in the width of the base flanges, which variation frequently happens in the rolling of the rails. If this provision were not made, it would be impossible to have the upturned portion or end 5 snap upward and engage one edge of the base flange.

I may, if desired, decrease the cross sectional area of the arm 6 so as to increase its resiliency without departing from the spirit of my invention.

Having fully described my invention, what I claim is:

1. A rail anchor formed of a single bar 20 of spring material circular in cross section and adapted to contact with the opposite edges of the base flanges of a railway rail at longitudinally spaced apart points and be out of contact with the underside of said flanges throughout the greater portion of their width, said anchor having a downturned end adapted to abut the side of a railway tie.

2. A rail anchor formed from a bar of 30 round spring material, means formed intermediate the ends of said bar to engage the top surface of a railway rail base flange on one side only and also to contact with the edge of said flange at one point, an upturned portion formed on one end of said bar and adapted to contact at one point only with the edge of the opposite base flange at a point longitudinally spaced from the first mentioned contact point the portion of the 40 bar adjacent its upturned portion being bowed away from the underside of said flanges, and a downturned portion formed on the opposite end of said bar, said downturned portion adapted to bear against the 45 side of a railway tie.

3. A rail anchor formed from a continuous round bar of spring material, certain portions of which are so bent as to contact

with the edge and top surface of one of the base flanges of a railway rail, and a downturned end integral with said bar adapted to contact with and bear against the side of a railway tie, when a rail creeps, said last mentioned portion adapted to act as a fulcrum for the anchor whereby the creeping of a rail will cause said anchor to turn so as to tightly bind at its contacting points with the edges of the base flanges of said rail thereby preventing same from creeping.

4. A rail anchor formed of a single piece 60 of elastic metal provided with resilient clamping jaws adapted to engage the base flange of a rail on its top and side edge at longitudinally spaced apart points, means integral with said anchor for engaging the 65 opposite side of the base flange of said rail, whereby lateral movement of said anchor is prevented, and one end of said anchor being downturned and adapted to bear against the side of a railway tie whereby 70 the creeping of a railway rail is prevented when said anchor is in position.

5. A rail anchor composed of a single piece of spring material which is provided intermediate its ends with jaws adapted to 75 receive one base flange of a railway rail and contact therewith at longitudinally spaced apart points on its upper and lower surfaces and at one point only on its edge, means integral with one end of said anchor for contacting with the edge of the opposite base flange at a point longitudinally spaced apart 80 from the first mentioned contact point, the opposite end of said anchor being turned downward from said anchor, said means adapted to contact with the side of a railway tie, and adapted to act as a pivot point for twisting said anchor on a railway rail when the same creeps thereby causing said points of contact of the anchor with the edges of 85 the base flanges to tighten on said edges and prevent the creeping of said rail.

In testimony whereof I have affixed my signature.

BENJAMIN B. BETTS.
